(57) **CLAIM**

The ornamental design for a bow handle design, as shown and described.

DESCRIPTION

FIG. 1 is a top front perspective view of the handle design.
FIG. 2 is a top rear perspective view thereof.

FIG. 3 is a top plan view thereof, with sectional designations referenced.

FIG. 4 is a bottom plan view thereof.

FIG. 5 is a front elevation view thereof.

FIG. 6 is a rear elevation view thereof.

FIG. 7 is a right side elevation view thereof.

FIG. 8 is a left side elevation view thereof.

FIG. 9 is an illustration aid of the handle design thereof.

FIG. 10 is a first sectional view along section 10-10 in FIG. 3.

FIG. 11 is a second sectional view along section 11-11 in FIG. 3.

FIG. 12 is a third sectional view along section 12-12 in FIG. 3.

FIG. 13 is a fourth sectional view along section 13-13 in FIG. 3.

FIG. 14 is top front perspective view of handle design of the present invention having a surface texture.

FIG. 15 is a top rear perspective view thereof.

FIG. 16 is a top plan view thereof.

FIG. 17 is a bottom plan view thereof.

FIG. 18 is a front elevation view thereof.

FIG. 19 is a rear elevation view thereof.

FIG. 20 is a right side elevation view thereof.

FIG. 21 is a left side elevation view thereof; and,

FIG. 22 is an enlarged perspective detailed view of detail 22-22 in FIG. 19.

The surface of FIGS. 1-20 are lightly lined for contour. The dash-dash lines indicate environmental subject matter and form no part of the claimed design. The dash-dot-dash lines designate the boundary of claimed subject matter in the cross-sectional views and confirm there is no claim to the inner surfaces of the design and form no portion of the claimed design. There is no claim to surfaces not shown. There is no claim to the inner portions or inner surfaces of the handle design. The dot-dash-dot broken line encircling the detailed view on FIG. 19 does not form any portion of the claimed design.
